(57) **CLAIM**

The ornamental design for a knife handle, as shown and described.

DESCRIPTION

FIG. 1 is a perspective view of a knife handle of my new design;

FIG. 2 is a left side view thereof;

FIG. 3 is a right side view thereof;

FIG. 4 is a bottom plan view thereof;

FIG. 5 is a top plan view thereof;

FIG. 6 is a front end view thereof; and,

FIG. 7 is a rear end view thereof.

The broken line portions of the drawings are included for the purpose of illustrating unclaimed structure and form no part of the claimed design.
